UNITED STATES PATENT OFFICE.

JOHN J. CROFT, OF ATLANTA, GEORGIA, ASSIGNOR TO CAPITAL CITY CHAIR COMPANY,
OF ATLANTA, GEORGIA, A CORPORATION OF GEORGIA.

REED FURNITURE.

1,427,581.

Specification of Letters Patent. Patented Aug. 29, 1922.

Application filed April 10, 1922. Serial No. 551,226.

To all whom it may concern:

Be it known that I, JOHN J. CROFT, citizen of the United States, residing at Atlanta, in the county of Fulton and State of Georgia, have invented certain new and useful Improvements in Reed Furniture, of which the following is a specification.

My invention relates to an improvement in that class of furniture made from fiber, reed, or rattan, woven in place to form the article of furniture desired, and more particularly to the settee, couch or chair shapes of such furniture, and which are provided with cushions to cover the seats of bottom thereof. In the use of such cushions it is found in practice that the weight of the person sitting thereon of necessity compresses the cushion, causing the edge to be pressed down and to project beyond the edge of the chair or other article of furniture to which the same is applied, thus presenting an unsightly appearance. The object of my invention is to construct the edge of the cushion-receiving portion of the furniture with what may be termed a guard or flange, and which extends above the seat of the chair or other article of furniture to which my invention may be applied to a distance about the height of the thickness of the cushion, or a distance approximately equal to the thickness of such cushion, whereby to confine the cushion in place and to prevent the edge extending beyond such seat.

In the accompanying drawing illustrating my invention as applied to a chair,

Fig. 1 is a perspective view of a reed or rattan chair showing my invention applied thereto;

Fig. 2 is a plan view of the seat form of the chair;

Fig. 3 is a front elevation of the seat portion with the stakes about which the reed or rattan is woven, and

Fig. 4 is a similar view showing a portion of the reed woven in place.

In the drawing, wherein like parts are designated by the same numerals, 5 designates a reed chair having a seat frame 6 provided adjacent its front edge 7, with a series of apertures 8 in which are mounted stakes 9 about which are woven the fiber

strands 10, said stakes being bent and turned downwardly as illustrated in Fig. 4 and hereinafter described.

As will be seen from Fig. 3, the ends of the individual stakes 9 are placed in one of the apertures 8 adjacent the front edge 7 of the bottom frame 6 to extend upwardly therefrom.

Fiber strands 10 are then woven in and out around the stakes 9 for a distance of from two to two and one-half inches above the seat frame 6. The stakes 9 are then bent over the front edge of the seat frame 6 with their free ends 11 extending downwardly toward the front legs 12 of the chair 5. The weaving of the fiber strands 10 is then continued about the stakes 9 to any depth desired and the free ends 11 of the stakes 9 are then secured to the legs 12 of the chair 5, as shown at 13—13, or to a separate section 14 of weaving, as illustrated in Fig. 1.

As will be seen that portion of the fiber which is woven in and about the stakes 9 and which extends above the front edge 7 of the seat frame 6 forms a guard or flange against which the edge of the cushion abuts, and is adapted to hold such cushion in place on the chair.

While I have shown my invention as applied to a chair, it will be understood that the same is equally applicable to other forms of reed furniture, such as settees and couches, or the like.

Having thus described my invention what I claim as new and desire to secure by Letters Patent is—

1. In reed furniture, a frame comprising front and rear upright members forming leg, side, arm, and back members, separate sections of reed extending between said back members, and separate sections of reed extending between said back members and said side and arm members, a bottom secured between said members adapted to receive a cushion, and a section of reed extending across the front of the frame and above the plane of the bottom whereby to form a guard for the front edge of the cushion and to hold the same in place.

2. In reed furniture, a frame comprising front and rear upright members forming leg,

side, arm, and back members, separate sections of reed extending between said back members, and separate sections of reed extending between said back members and said side and arm members, a bottom secured between said members adapted to receive a cushion to be held on its rear and sides by

said back and side members, and a section of reed extending across the front of the frame and above the plane of the bottom whereby to form a guard for the front edge of the cushion and to hold the same in place. 10

JOHN J. CROFT.
